United States Patent Office

Des. 233,864
Patented Dec. 3, 1974

233,864

TWEEZER OR SIMILAR ARTICLE

Edgar M. McClure, Roanoke, Va., assignor to
Scientific Components, Inc., Roanoke, Va.

Filed Jan. 3, 1973, Ser. No. 320,816

Term of patent 14 years

Int. Cl. D8—05; D24—02

U.S. Cl. D86—10 B

FIG. 1 is a tweezer or similar article showing my new design;

FIG. 2 is a side elevation thereof;

FIG. 3 is a top plan view thereof;

FIG. 4 is a perspective view of a modified embodiment of the form shown in FIG. 1; and

FIG. 5 is still a further embodiment of the form shown in FIG. 1.

I claim:

The ornamental design for a tweezer or similar article, as shown and described.
